UNITED STATES PATENT OFFICE

1,968,730

WEIR

Hans Zimmermann, Dortmund, Germany, assignor to the firm Vereinigte Stahlwerke, Aktiengesellschaft, Dusseldorf, Germany

Application August 22, 1932, Serial No. 629,927
In Germany February 24, 1931

6 Claims. (Cl. 61—26)

The present invention relates to weirs having a movable superimposed falling board or flap and has for its object to improve the side confines of the water flowing over the flap and to improve 5 the tight fitting of the side of the flap against the weir itself.

In known arrangements of these superposed flaps, shields are arranged on the weir itself, for the purpose of confining the overflow at the side, 10 the flap sliding tightly against the surfaces of the shields facing the water. If in such cases the weir recess has to be sealed against any overflow water, then the side shields must extend over the whole width of the recess. This however gives 15 rise to certain difficulties in the arrangements for moving the flap, since the flap actuating means must either go round the lateral shields or through them. In the case of flaps which, for the purpose of preventing the weir itself from 20 being wetted by water overflowing, are made as wide as the weir itself, there will obviously have to be a considerable length of the lateral seal. Furthermore the seal must be affixed to the movable flap and this renders difficult access to, and 25 re-tightening of, leaking sections because the overflow water entirely shuts off the space under the flap where the re-tightening has to be carried out and which is also enclosed on top by the pent water and at the sides by the shields.

30 The present invention overcomes these difficulties by the fact that the side confinement of the water stream which flows over the flap is effected by a shield which is connected with the flap and which projects behind a side wall of the 35 weir body against which wall the shield is sealed by a tight sliding means extending over the whole height of the flap. The seal is stationary and can therefore be easily re-tightened from the recess, in any position of the flap while the operator 40 is in a perfectly dry place. The weir wall which cooperates with the side shield must not extend over the beginning or the axis of rotation of the flap so that no structural part of the weir as hereinbefore rests between the actuating 45 means and the flap. The actuating means of the flap can therefore be directly secured thereto regardless of the leverage about the axis of rotation of the flap. By arranging the flap sealing means on the high water side of the space over 50 which the flap extends, it is ensured that if the seal at the side should leak, the space under the flap does not freeze in winter and hinder the movements of the flap.

In order to illustrate the invention the drawings Nos. 1 to 4 are attached.

Figure 1 is a partial cross section through the weir and the flap showing the side shield in side elevation.

Figure 2 is the corresponding plan.

Figures 3 and 4 are an elevation and a ground plane respectively of a particular form of application of the side seal and its re-tightening device.

Fig. 5 is a (partial) longitudinal section of the re-tightening device according to line 5—5 of Fig. 4, and

Fig. 6 is a plan view according to Fig. 5.

In Figures 1 and 2, 1 is the weir itself, 2 is the flap, 3 is a side wall affixed to the weir itself, 4 is the fixed side seal of the flap, 17 is the means for raising the flap, which may engage, for example, at 5 with the bolt 7 which is arranged on the flap and projects into the weir recess, 18 is the means for lifting the weir which is connected at 6 to the weir. 8 is the water flow when the flap 2 has been lowered through an angle α into the position 2' which is shown in dotted lines. 9 is a side shield which is arranged on the flap and projects towards the high water level behind the wall 3 on the air side thereof in such a way as to engage the said wall laterally. The position of the side shield 9 when the flap 2 has been lowered into the position 2' is shown at 9' in dotted lines. 10 is the space between the side shield 9 on the flap and the side wall 3 of the 75 weir, which is free from water and in which the means for re-tightening the sealing device for the flap can be arranged.

It is readily seen that the length of the lateral seal is limited to the effective height h of the flap, and that no matter at what angle the flap may rest, its position is unaltered.

Figures 1 and 2 also show that no water can enter into the space under the flap, because the side shield of the flap is firmly connected with its wall so that no impediment to the movement of the flap can result from the formation of ice. These drawings also show that the re-tightening means for the seal of the flap, which are arranged in the space 10, are accessible from the recess at all positions of the flap and even while the water is flowing over. It is further evident that the means 17 for raising the flap 2 can be secured thereto within the recess at any desired place, without interfering with any other structural parts of the weir.

In Figures 3 and 4, the parts which are shown in Figures 1 and 2 are marked by the same reference numbers. Thus 1 is the wall of the weir itself, 2 is the flap, 3 is the side wall of the weir, 110

4 is the resilient side seal for the flap, 9 is the shield affixed to the flap, 10 is the space between the walls 3 and 9, 11 is an eccentric shaft which rests in bearings at 12 and 13 on the weir itself or on its side wall 3 which serve also for mounting the seal 4, 14 is a ratchet wheel which is wedged on to the eccentric shaft 11 and with which engages a pawl 15; 16 is a spanner by which the eccentric shaft 11 can be rotated.

10 Figures 3 and 4 illustrate a particularly simple design for re-tightening the seal 4 and are meant to illustrate the advantage of the present invention, which consists in that the sealing member can be re-tightened, mounted and removed easily 15 from the recess no matter what the position of the flap may be. If the sealing device is to be re-tightened, when the spanner 16 is put on to the upper end of the eccentric shaft 11 and the shaft is rotated in a direction to tighten the seal 20 4 against the walls 3 and 9 until the requisite seal is accomplished. After tightening of the seal the pawl 15 will help to maintain the tightening pressure. If the seal is to be removed then the upper 25 shaft bearing 13 is removed and the shaft 11 and the seal 4 are taken out in an upward direction, whereupon the new seal and, after that, the eccentric shaft 11 are put into position from above.

In Figures 5 and 6 the re-tightening means are more clearly shown; in Fig. 5 which is a section seen from the up-stream side towards the down-stream side, 11 is the shaft of the tightening device which is rotatably mounted between the side shield 9 of the flap and the side wall 3 of the weir in the bearing plates 12 and 13 by means of the eccentrically disposed pivots 19 and 20, the upper pivot 16 being provided with the ratchet wheel 14 and a square-head for engagement of a spanner 16 (see Fig. 3). A pawl 15 which is rotatably mounted on the plate 13 is held in engagement with the ratchet wheel 14 by means of a spring 21 (see Fig. 6).

In the above description the present invention is illustrated as applied to a flood weir. It is however not limited to this type of weir but can be used to advantage with all weirs which can be provided with superimposed flaps. In the place of the seal and the re-tightening means for the same which have been illustrated in Figures 3 and 4, and described hereabove, other such means can be used which are arranged in the space 10 between the walls 3 and 9 and can be mounted and operated from the recess without departing from the spirit of the invention. As

far as the invention is concerned, it does not matter whether the side shield 9 of the flap 2 is arranged on the air side or on the water side of the side wall 3 of the weir 1 provided that the water flow 8 is either totally or partly confined by the side shield 9 in relation to the recess. 80

What I claim and desire to secure by Letters Patent is:—

1. A weir of the type having a superimposed flap, comprising a side wall to said weir, a shield secured to said flap at its side to confine water flowing over said weir and projecting behind said wall on the air side thereof, and a seal between said wall and said shield of a length substantially equal to the maximum effective height of said flap. 85

2. A weir of the type having a superimposed flap, comprising a side wall to said weir, a recess on the air side of said side wall, a shield secured to said flap at its side to confine water flowing over said weir and projecting behind said wall on the air side thereof, a seal between said wall and said shield of a length substantially equal to the maximum effective height of said flap, and means accessible at all times from said recess for 100 tightening said seal. 95

3. A weir as claimed in claim 2, wherein said means comprise bearings in said weir wall, a shaft eccentrically mounted in said bearings, and means to rotate said eccentric shaft to tighten 105 said seal.

4. A weir as claimed in claim 2 wherein said means comprise bearings in said weir wall, a shaft eccentrically mounted in said bearings, a ratchet wheel upon said shaft, a pawl engaging 110 said ratchet wheel, and a spanner to turn said shaft to tighten the said seal. 115

5. A weir of the type having a superimposed flap, comprising a side wall to said weir, a shield secured to said flap at its side to confine water flowing over said weir and projecting behind said wall, and a seal between said wall and said shield. 120

6. A weir of the type having a superimposed flap rotatable about an axis on the weir, comprising side walls secured to the weir, side shields secured to the flap for preventing water from flowing off laterally, said shields projecting towards the high water side behind the said walls, stationary seals between the said shields and the said walls, the said walls extending with their edge directed towards the low water side to the axis of rotation of the flap. 125
